CLAIM

The ornamental design for a stackable shoe rack, as shown and described.

DESCRIPTION

FIG. 1 is a front perspective view of a stackable shoe rack, showing my new design;

FIG. 2 is a top plan view thereof;

FIG. 3 is a front elevational view thereof;

FIG. 4 is a side elevational view taken from the right in FIG. 1, the left side being a mirror image thereof;

FIG. 5 is a rear elevational view thereof;

FIG. 6 is a bottom plan view thereof; and,

FIG. 7 is a front perspective view of a stackable shoe rack showing a second embodiment of my design.

FIG. 1

FIG. 4

FIG. 2

FIG. 3

FIG. 5

FIG. 6

FIG. 7
